UNITED STATES PATENT OFFICE

159,988

POWER-OPERATED PLATFORM TRUCK

Daniel C. Jones, Port Washington, Wis., assignor
to Kwik-Mix Company, Port Washington, Wis.

Application March 31, 1949, Serial No. 1,724

Term of patent 14 years

(Cl. D14—3)

To all whom it may concern:

Be it known that I, Daniel C. Jones, a citizen of the United States, residing at Port Washington, in the county of Ozaukee and State of Wisconsin, have invented a new, original, and ornamental Design for Power-Operated Platform Truck, of which the following is a specification, reference being had to the accompanying drawing, forming part thereof, wherein:

Figure 1 is a side elevation of a platform truck embodying my new design.

Figure 2 is a side view looking in the direction opposite that from which Figure 1 is taken.

Figure 3 is a front end view.

Figure 4 is a rear view.

Figure 5 is a top plan view.

I claim:

The ornamental design for a power-operated platform truck, substantially as shown.

DANIEL C. JONES.
